(57) CLAIM

The ornamental design for a shirt with hood, as shown and described.

DESCRIPTION

FIG. 1 is a front view thereof;

FIG. 2 is a rear view thereof; and,

FIG. 3 is a side view of the hood portion; the body of the shirt shown removed for ease of illustration.

The portions shown in broken lines are for illustrative purposes only, and form no part of the claimed design.

1 Claim, 3 Drawing Sheets

FIG. 3
